UNITED STATES PATENT OFFICE.

THOMAS HIBBARD, OF BOSTON, MASSACHUSETTS.

METHOD OF LAYING UNDERGROUND PIPES.

SPECIFICATION forming part of Letters Patent No. 289,000, dated November 27, 1883.

Application filed July 24, 1882. (No model.)

To all whom it may concern:

Be it known that I, THOMAS HIBBARD, residing at the city of Boston, in the county of Suffolk and State of Massachusetts, have invented certain new and useful Improvements in the Method of Laying Underground Pipes for Water, Gas, Electric Conductors, &c., of which the following is a full and clear specification.

10 The object of my invention is to do away with the great expense and inconvenience incurred, especially in the crowded streets of cities, in the customary method of laying pipes under ground by trenching, laying, and filling in; and said invention consists of a process 15 of driving the pipe through the earth horizontally, or slightly inclined therefrom, by rotating said pipe on its own axis, with a jet of water carried within its forward end, arranged 20 to be used alone or in connection with a suitable boring-tool, for the purpose of loosening and removing the obstructing earth, while the pipe is fed forward automatically through the channel thus opened before it, and remains 25 permanently in said channel when bored to the desired distance. One form of apparatus by which this result may be accomplished is shown in the accompanying drawings. As it 30 is most advantageous to use a motor as a source of mechanical power for the performance of the necessary operations, I have represented one in the drawings consisting of a boiler and pair of vertical engines resting on a common bed-plate.

35 Figure 1 represents a longitudinal section through a street, showing the line of pipe being laid or driven, and a front elevation of the motor and turning apparatus. Fig. 2 is a cross-section of the street, with an end elevation 40 of the pipe-driving machinery. Fig. 3 shows a plan of the same. Figs. 4, 5, and 6 are longitudinal sections through the leading end of a line of pipe, showing some of the various tools and devices that may be employed to 45 open a passage for the advancing pipe. Fig. 4 shows an ordinary earth-auger with a water-pipe arranged just back of it to throw a jet upon the débris collected within the permanent pipe, for the purpose of washing it back 50 to and out of the rear end. Fig. 5 represents a combination of boring-tool and jet of water

for opening the passage; and Fig. 6 represents the manner of boring when using water alone. Fig. 7 is a cross-section through the pipe, taken on *n n* in Fig. 4.

55

In Figs. 1, 2, and 3, A represents the pavement of a street or sidewalk, or the surface of the ground, as the case may be, and B the earth or soil beneath.

C is the line of pipe being laid, with the 60 boring-tool K on its forward end, and C' is the forward or leading end of the length of pipe previously driven.

D is the boiler and E the engines erected over the trench N, which is dug in the ground 65 for a starting-point.

G is a hollow shaft or spindle, in which a piece of pipe is centered and held while turning by means of the chuck F, which is firmly attached to said shaft. Said shaft is rotated 70 by means of the gear S, which meshes with the pinion on the crank-shaft of the engines, and is arranged to slide through said gear S, while being rotated, by means of a feather in the hub of said gear, which feather fits in a 75 keyway in the shaft G. The shaft G has a thread cut on its rear end, which is acted on by a nut in the hub of the brake-wheel H, so that when said wheel and nut are prevented from turning by the friction of the brake-strap I, 80 applied through the hand-lever J, the spindle G advances as it is turned. The shaft G, with parts attached, is suspended in suitable frames, which hang from the crank-shaft of the engines, and around which they can be rotated 85 until the shaft G rises above the ground-level, as shown by dotted lines in Fig. 2.

P is a steam-pump, with its suction-pipe T arranged to draw water from the tank M, and its delivery-pipe U connecting with the small 90 pipe L, which extends within the permanent pipe C to its leading end, as shown in Figs. 4, 5, and 6. The forward end of the water-pipe L is provided with a nozzle, R, directed forward or backward, as the case may be. The 95 water-pipe is supported and held to one side of the pipe C by means of the supports O, placed at intervals, and shaped to obstruct as little as possible the passage of the débris as it is washed out of the pipe. The tank M is placed 100 to catch the washings as they fall from the pipe C, and is provided with strainers for the

then be attached to the obstructed pipe by means of offsets or any other method commonly used in such emergencies.

This process of laying pipe is especially applicable to establishing systems of subterranean pipes for inclosing electric cables or conductors. Such pipes are usually laid from two and one-half to three feet below the surface, and they are provided with boxes opening to the surface at intervals of one hundred to four hundred feet, for the purpose of drawing in and repairing wires. At the locations of these "joint-boxes," so called, I should erect my machinery, making my lines of pipes long enough to reach from box to box. Thus the surface of the ground would not be disturbed oftener than necessary.

It is evident that a great many different kinds of tools and arrangements of turning apparatus may be successfully used in laying pipe by this process, and I wish it understood that I do not confine myself to the particular devices shown in the accompanying drawings.

I claim—

1. The above-described process of driving pipes positively through the ground, which consists in carrying along within said pipe, by a smaller pipe, a stream and jet of water to loosen

the earth in advance of the pipe, and by said forcing-jet washing and driving the earth back through and out of said pipe, as set forth.

2. The above-described process of driving pipes positively through the ground, which consists in carrying a boring-tool at the forward end of said pipe, and a stream and jet of water within said pipe, by means of a smaller pipe, to wash and drive the earth displaced by said boring-tool back through and out of said pipe, substantially as herein specified.

3. The above-described means for driving pipes horizontally through the ground, consisting of a motor provided with devices for centering, rotating, and feeding forward said pipe, in combination with a pump, P, arranged to draw water from a tank, M, force said water into the pipe L and out of the nozzle R at its forward end, from which said water may return in the outer pipe, C, and fall from its rear end into said tank M, so that said water may be used over and over again, all as herein shown and described.
